UNITED STATES PATENT OFFICE.

LUCIUS E. WEAVER, OF EAST HAMPTON, CONNECTICUT, ASSIGNOR TO SUMMIT THREAD COMPANY, OF EAST HAMPTON, CONNECTICUT, A CORPORATION OF MAINE.

BOBBIN FOR SEWING-MACHINE SHUTTLES.

1,278,262.

Specification of Letters Patent. Patented Sept. 10, 1918.

Application filed January 28, 1918. Serial No. 214,116.

To all whom it may concern:

Be it known that I, LUCIUS E. WEAVER, a citizen of the United States, residing at East Hampton, in the county of Middlesex 5 and State of Connecticut, have invented new and useful Improvements in Bobbins for Sewing-Machine Shuttles, of which the following is a specification.

This invention relates to a bobbin for use 10 with a sewing-machine shuttle having a bobbin chamber, inner and outer bobbin abutments at opposite ends of the chamber, the said bobbin comprising a body tube surrounded by a winding of thread, and heads 15 detachably engaged with opposite ends of the tube, the bobbin being rotatable between said abutments to give off thread, and the outer abutment being displaceable to permit the insertion and removal of the 20 bobbin. The object of the invention is to provide an improved construction of one of said heads, whereby the head is equipped with an inseparably connected tension device adapted to prevent objectionably free 25 rotation of the bobbin, so that the bobbin is not liable to be rotated by its own momentum faster than the call for the thread, and cause slack thread in the chamber or between the winding of thread on the bobbin 30 and the usual tension devices being therefore prevented.

The invention is embodied in the improvements which I will now proceed to describe and claim.

35 Of the accompanying drawings forming a part of this specification,—

Figure 1 is a side view of a rotary shuttle to which my invention is applicable.

Fig. 2 is a section on line 2—2 of Fig. 1.

40 Fig. 3 is a plan view of one of the bobbin heads.

Fig. 4 is a section on line 4—4 of Fig. 3.

Fig. 5 is a longitudinal section of a reciprocating shuttle to which my invention 45 is applicable.

The same reference characters indicate the same parts in all of the figures.

Referring first, to Figs. 1 and 2, which 50 show a shuttle which may be either rotated or oscillated in the performance of its function, 12 represents the arcuate body of the shuttle, and 13 the beak thereof. In this type of shuttle the bobbin is held in a chamber formed by a cylindrical bobbin-case 14, 55 open at its outer end and closed at its inner

end, the latter being provided with an ear 15 which is connected by a pivot stud 16 with the body 12, so that the bobbin-case may be swung laterally relatively to the body, to permit the insertion and removal 60 of a bobbin. The closed end of the bobbin-case is provided with a stud or post 17, which constitutes an inner bearing or abutment for the bobbin. One end of the body 12 is provided with a finger 18 which projects over the open end of the bobbin-case 14, and constitutes a stop or outer abutment, preventing the removal of the bobbin when the bobbin-case and shuttle body are in their normal relative positions.

The bobbin shown by Fig. 2 includes a tubular body 19, which is preferably a cop tube of paper, or like material, on which is formed an annular winding 20 of thread, by what is known as a universal winding 70 operation, the cop tube and the body of thread wound thereon constituting in effect a single part of the bobbin, adapted to be stored, marketed, and handled as such, the bobbin being completed by assembling with 75 the tubular body 19 and thread winding 20, an inner head 21, and an outer head 22. These heads are adapted to be separably and frictionally engaged with the ends of the tubular body 19, each head having a stud 80 formed to closely fit the bore of said body, and to be retained therein by friction, the stud being removable from the body.

The construction of the bobbin and shuttle thus far described is common and well 90 known, the head 22 being provided with a stud 23 which is solid, as usual. Heretofore, the stud on the opposite head 21 has also been solid, the head 21 and its stud being duplicates of the head 22 and stud 23. It 95 has been customary heretofore to allow the central portion of the head 21 to bear directly on the inner abutment 17, the head 22 bearing at the same time on the outer abutment 18. The abutments 17 and 18 are 100 spaced apart to permit the bobbin to be inserted loosely between them. The bobbin is therefore adapted to rotate so loosely between the abutments 17 and 18 that when the bobbin is rotated by the thread pulled therefrom, the rotation of the bobbin is liable to be continued by the momentum of the bobbin, to such an extent that loose thread accumulates in the bobbin-case, or between the winding 20 on the bobbin and 110

the usual tension spring 24 on the bobbin-case. This accumulation of loose thread is often a serious objection.

To overcome the above-mentioned objection, I provide the bobbin with a spring-pressed member, yieldingly projecting from one of its heads, and adapted to bear on the inner abutment 17, and press the other head against the outer abutment 18, with sufficient force to create a frictional resistance to the rotation of the bobbin sufficient to prevent the bobbin from being rotated by its own momentum.

Said spring-pressed member is a plunger 25, movable endwise in the body-engaging stud 26 of the head 21, said stud being tubular, as best shown by Fig. 4. The inner end of the stud 26 is provided with an inwardly projecting flange 27, constituting a guide for the reduced stem or shank portion of the plunger, a stop member co-operating with a complementary stop member on the plunger, and an abutment for one end of a helical spring 28. The plunger is provided with an enlargement 29, having a sliding fit in the bore of the stud 26, and constituting a shoulder on which the opposite end of the spring 28 bears. The shank of the plunger 25 is enlarged or upset to form a head 30, located outside the stud and adapted to bear on the flange 27 as a complementary stop member, said head and flange limiting the projection of the plunger from the head 21 by the spring 28.

As shown in Fig. 4, when the head 21 is removed from the shuttle, the plunger 25 is projected from the outer face of the head 21 as far as the stop members 27 and 30 permit. As shown by Fig. 2, when the bobbin is inserted in the shuttle, the plunger 25 bears on the inner abutment 17, and is caused, when the outer bobbin 18 is in place, to press the outer head 22 against the abutment 18, the spring 28 being compressed and acting to press the head 22 against the abutment 18 with sufficient force to prevent the bobbin from being rotated by its own momentum. Provision is therefore made for preventing the liability of an accumulation of loose thread in the bobbin-case or chamber.

The plunger 25 is preferably in axial alignment with the bobbin body 19, and the inner abutment 17 is preferably provided with a recessed step 31 engaging the outer end of the plunger, as shown by Fig. 2.

As shown by Fig. 5, my invention may be embodied in a reciprocating shuttle 32, the body of which has a bobbin chamber 33, closed at one end and having in its closed end a recessed step 31 engaging the plunger 25. The bobbin is in all respects, excepting size and proportion, a duplicate of the bobbin above described, the inner head 21 being provided with a tubular stud in which

the plunger 25 is movable, and the outer head 22 being pressed by the plunger and its spring against an outer abutment 34 at the open end of the bobbin chamber 33. The spring-pressed member 25 is located mainly within the bobbin body, and the spring 28 is located wholly within said body, so that the application of said member and spring to the bobbin does not require a reduction of the thread-storing capacity. 75

It will now be seen that the bobbin is distinguished from sectional bobbins as heretofore made, by the fact that the bobbin includes a combined bobbin member and tension device embodied in the head 21, tubular stud 26, plunger 25, and spring 28. The stop member 30 on the plunger is outside the stud, so that it may be formed by upsetting the inner end of the plunger after the insertion of the plunger in the stud. After the stop member 30 is formed, the plunger is inseparably connected with the stud and head, its outward movement being limited by the stop members 27 and 30, and its inward movement by the stop member 27 and spring 28. 80

It will also be seen that the head 21, formed to cover one end of a winding of thread on a cop tube, and having means for frictionally engaging said tube, and the tension device which includes the spring 28 and the plunger 25, are permanently connected by the means illustrated, so that the head and tension device are adapted to be applied to and removed from the cop tube as a single part. The operation of assembling the cop tube, with its winding, and the heads 21 and 22, therefore provide the bobbin with a tension device which is a part of 100 the bobbin and is rendered operative by the insertion of the bobbin in the shuttle. 105

I claim:

1. In a shuttle bobbin of the character stated, a bobbin head formed to cover one end of a winding of thread on a cop tube forming a part of the bobbin, said head being provided with a fixed tubular stud projecting from its inner side and formed to enter and frictionally engage the cop tube, and having a fixed spring abutment, the head being also provided with a tension device including a spring seated on said abutment, and a plunger movable in the stud and adapted to be projected by said spring from the outer side of the head, stop means being provided for limiting the projection of the plunger by the spring. 110

2. In a shuttle bobbin of the character stated, a combined bobbin member and tension device comprising a bobbin head, a tubular stud projecting from the inner side of said head, and adapted to frictionally engage a cop-tube, said stud being provided at its outer end with an inwardly project- 115 120 125 130

ing annular flange contracting a portion of the bore of the stud, and constituting a spring abutment, said bore extending from the outer side of the head to said flange, a 5 plunger having an enlarged portion fitting and movable in said bore, and a reduced portion fitting and movable in said flange, and a spring interposed between said flange and the enlarged portion of the plunger, and

exerting outward pressure on the plunger, 10 the reduced portion of the plunger being provided with a stop member located outside the stud and coöperating with said flange in limiting the outward movement of the plunger by the spring.

In testimony whereof I have affixed my 15 signature.

LUCIUS E. WEAVER.
